ATTORNEYS

UNITED STATES PATENT OFFICE.

JAMES LOGAN, OF WATERLOO, NEW YORK.

GRAVE RECEPTACLE OR VAULT.

SPECIFICATION forming part of Letters Patent No. 275,833, dated April 17, 1883.

Application filed January 19, 1883. (No model.)

To all whom it may concern:

Be it known that I, JAMES LOGAN, a citizen of the United States of America, residing at Waterloo, in the county of Seneca and State of New York, have invented certain new and useful Improvements in Grave Receptacles or Vaults, of which the following is a specification, reference being had therein to the accompanying drawings.

10 My invention relates to vault-receptacles for coffins, said vault consisting of artificial stone made in the ground by means of the portable mold granted to me in Letters Patent No. 265,522, October 3, 1882.

15 It further consists in a vault cap or cover and rest for same, all of which will be more fully set forth in the specification and pointed out in the drawings, in which—

20 Figure 1 is a perspective view of the several elements involved in my device, and Fig. 2 a section of the vault when covered by the cap and artificial stone.

25 Referring more particularly to the drawings, the receptacle A is made of any suitable artificial stone that will quickly harden and be impervious to water. I preferably use hydraulic cement and sand, as being cheap and readily obtained. In this connection I use the portable mold above referred to, the sections of the mold being made rectangular instead of circular, as shown in my patent above referred to.

30 The construction and operation are as follows:

35 The grave is dug of a larger size than the mold, and a layer of the artificial stone placed in the bottom of the grave, and the mold placed on this layer and the cement poured between the mold and earth. The mold is allowed to remain until this substance has set. The mold is then removed and the coffin-rests C slipped down into the grooves e, molded on the inside of the vault for this purpose. The coffin is supported by these rests, and is raised 40 sufficiently above the bottom of the vault to permit the ready removal of the lowering cords or straps. The cross-bars d are then placed in the openings g in the top of said rests to support the cover or cap B. This cap 45 is made of sheet metal or wood, or part wood and part metal. On the top of the cap are

50 two hooks or catch-pieces, b b, by means of which the cap is lowered so as to rest on the cross-bars d. This cap comes just to the inside edges of the newly-made vault, and after 55 being placed in position is covered with the artificial stone in the form of an arch, as shown at G, Fig. 2, the stone covering being of a corresponding thickness with the sides of the vault, and "sets" or hardens with said sides, 60 so as to form an integral vault and cover. The earth is thrown on this cover and the grave filled up. The rests C are made of wood or iron; but I prefer to use cast-iron. The cross-bars d are also made of wood or iron. The vault 65 is made about two or three inches higher and wider than the coffin-box.

A vault constructed of the material and in the manner described is air and water tight and will preserve the coffin and remains for 70 ages. By means of the rests C and the cross-bars the weight of the cap and superincumbent mass of earth is distributed over the bottom of the vault, and the danger and liability of breaking the stone covering G are therefore 75 avoided.

Having thus described my invention, what I claim is—

1. A grave vault or receptacle made of artificial stone in the manner described, and provided with grooves or channels in the sides for the reception of coffin-supports, substantially as and for the purpose set forth.

2. A grave-vault made of artificial stone and provided with one or more interior removable coffin-supports, whereby the coffin is raised above the bottom of said vault, as and for the purpose set forth.

3. A grave-vault, as described, in combination with the coffin-supports, and a detachable cover resting upon said supports and adapted to receive and support a covering of artificial stone and the superincumbent earth, as and for the purpose set forth.

4. The combination, with a grave-vault, of a detachable cover provided with hooks or catches, whereby the cap can be lowered on the vault and the lowering means removed, as set forth.

5. The coffin-supports C, having recesses in their top for the reception of cross-bars d, and adapted to enter grooves in the sides of the

vault and support the coffin above the bottom of the vault, as set forth.

6. The combination, with a grave-vault of artificial stone, made as described, of the coffin supports, and a detachable cover or cap provided with hooks or catches, said cover or cap being covered with artificial stone, which, when set, becomes integral with the vault, and thus renders it air and water tight, substantially as set forth.

In testimony whereof I affix my signature, in presence of two witnesses, this 18th day of January, 1883.

JAMES LOGAN.
